(57) **CLAIM**

The ornamental design for a personal massager, as shown and described.

DESCRIPTION

FIG. 1 is a right side perspective view of a personal massager showing my new design.

FIG. 2 is a top plan view thereof.

FIG. 3 is a right side plan view thereof.

FIG. 4 is a left side plan view thereof.

FIG. 5 is a bottom plan view thereof.

FIG. 6 is a rear plan view thereof.

FIG. 7 is a front plan view thereof.

FIG. 8 is a right side perspective view of a second embodiment thereof.

FIG. 9 is a top plan view of the second embodiment thereof.

FIG. 10 is a right side plan view of the second embodiment thereof.

FIG. 11 is a left side plan view of the second embodiment thereof.

FIG. 12 is a bottom plan view of the second embodiment thereof.

FIG. 13 is a rear plan view of the second embodiment thereof; and,

FIG. 14 is a front plan view of the second embodiment thereof.

The broken lines represent portions of the personal massager that form no part of the claim.
